ICE INHIBITING ASSEMBLY FOR AIRPLANES

Edward B. Benson, Kansas City, Mo., assignor to
 The Benson Mfg. Co., Kansas City, Mo., a corporation of Missouri

Application February 26, 1938, Serial No. 192,837

6 Claims. (Cl. 244—134)

My invention relates to an ice inhibiting assembly for airplanes and more particularly to an assembly for preventing the accumulation of ice on propeller blades of an airplane propeller.

5 Airplanes frequently fly through atmospheric conditions which are conductive to the rapid formation of ice. When moisture is deposited on a moving plane at or near the freezing temperature, the further lowering of the temperature due 10 to the evaporation of a portion of the moisture causes the remaining moisture to freeze and form ice. The airplane propeller moving through the air at a higher speed than the plane itself is particularly subject to the accumulation of ice deposits when atmospheric conditions are such that 15 ice will form. The deposit of ice on an airplane propeller blade not only changes the shape of the propeller blade so as to render it less efficient but results in an unbalancing of the effective 20 weight of the propeller blades. This introduces serious vibration and constitutes an added danger to the operation of the aircraft.

It has been suggested to provide means for feeding an anti-freezing mixture such as a mixture 25 of glycerine and alcohol, and the like, along each blade of the propeller and it has been found that this will prevent the formation of ice deposits on propeller blades, even under severe icing conditions.

30 The mounting of such arrangements has been a difficult task. The arrangement is subjected to the high centrifugal speed of the propeller. The propeller blades are constantly vibrating and the combined vibratory and centrifugal load, as 35 well as the shock loads introduced by starting and stopping, impose a severe strain upon the ice inhibiting assembly. Then, too, the weight of the assembly must be kept at a minimum, as weight distribution is an important factor in airplane design.

40 It has been found that devices of the prior art, after operation for a comparatively short period of time, show failure, due to the shock loading conditions of use. The average length of service 45 of the devices of the prior art has been about one hundred hours.

One object of my invention is to provide an ice inhibiting assembly for airplane propellers, which can be readily mounted without the necessity of 50 aligning and balancing the assembly after mounting.

Another object of my invention is to provide an ice inhibiting assembly for airplane propellers and more particularly a variable pitch propeller 55 unit which is expeditiously and conveniently re-

movable for the servicing of the variable pitch propeller mechanism.

Another object of my invention is to provide an ice inhibiting assembly which is light in weight and simple in construction.

Another object of my invention is to provide an ice inhibiting assembly in which the deleterious effect of vibration of the propeller blades is minimized.

Other and further objects of my invention will 10 appear from the following description.

In the accompanying drawings which form part of the instant specification and are to be read in conjunction therewith and in which like reference numerals are used to indicate like parts 15 in the various views;

Figure 1 is an elevation of my ice inhibiting assembly, mounted upon an airplane propeller.

Figure 2 is a sectional elevation of the assembly shown in Figure 1.

Figure 3 is a sectional view taken on the line 20 3—3 of Figure 2.

Figure 4 is a perspective view of an adapter used in carrying out my invention.

Figure 5 is a sectional view taken on the line 25 5—5 of Figure 3.

Figure 6 is a sectional view taken on the line 6—6 of Figure 5.

Figure 7 is a bottom plan view of one of the 30 securing means used in my assembly.

Figure 8 is a sectional view taken on the line 8—8 of Figure 7.

Figure 9 is a side elevation of one of the coacting parts of the securing means used in my assembly.

In general, my invention contemplates the provision of adapters of light and strong construction, mounted upon the propeller hub between the propeller blades and adapted to hold a slinger ring construction and a nose spinner construction by means of readily detachable spring and cam fasteners whereby the slinger ring and nose spinner are substantially flexibly mounted.

More particularly, referring now to the drawings, an airplane propeller having blades 1 is 45 mounted on an engine shaft forward of the airplane engine cowling 2. The propeller blades 1 are supported by propeller hub 3. In the drawings, a variable pitch propeller is shown and the reference numeral 4 indicates a portion of 50 the variable pitch propeller mechanism. It is understood, of course, that the showing of a variable pitch propeller is by way of illustration only, as my invention may be used with any type of airplane propeller. The hub 3 is formed with 55

lugs 5, through which bolts 6 are adapted to pass to hold the two portions of the hub together. According to my invention, I provide adapters such as shown in Figure 4. The adapters comprise channel members, each having a face 7, which is curved along the radius of a pair of rings 8 and 9, which are adapted to support the slinger ring 10 and the nose spinner 11, respectively. Flanges 12 and 13 are reinforced by corrugated members 14 and 15, secured to the flanges by rivets 16, thus forming laminated side members of great strength for the weight of material. The side members are provided with openings 17, 18, 19, and 20. Opening 17 is directly opposite opening 19 and opening 18 is directly opposite opening 20, and the openings are provided for the reception of the hub bolts 6, as will be readily apparent from reference to Figure 5. In the prior art, the point of greatest strain has been at the locus of connection of the adapters to the hub. To strengthen the adapters further, I provide patches 21, positioned on both sides of respective openings 17, 18, 19, and 20, and riveted to the flanges 12 and 13. The face 7 is formed with lightening openings 22. The edge of the flanges 12 and 13 are turned to form smaller flanges 23 and 24. Each adapter supports an ice inhibiting fluid distributing conduit 25, adapted to receive fluid from the slinger ring and conduct it to the base of the propeller blade 1. Respective after ends of fluid distributing conduits 25 are provided with flanges 26, adapted to be secured to the slinger ring.

The face 7 of each adapter is provided with a pair of rows of openings 27. Positioned across each opening 27 is an S-shaped spring 28. The ends of each spring are riveted to the face 7 of the adapter by respective rivets 29. An S-shaped spring 28 and its securing rivets 29 are shown on the enlarged sectional view in Figures 7 and 8. It will be observed that the S-shaped spring extends directly across each opening 27. Each spring 28 is adapted to coact with a fastening means shown in detail in Figure 9. The fastening means 30 is formed with a body portion 31 and a head 32, the head being provided with a slot 33 adapted to receive a screw driver. The body portion is provided with a cam slot 34 in the form of a high pitch helix. The end of the cam slot 34 terminates in a seating groove 35. The width of the cam slot 34 is such that the S-spring will enter into the cam slot and, upon rotation of the member 30, the fastening means will be forced downwardly, compressing the spring and permitting it to seat in the seat 35. If desired, a washer 36 may be placed between the head 32 of the fastening means and the sheet 9, clamped between the head 32 and the face 1 of the adapter. It is understood, of course, that the fastening means 30 is adapted to be inserted through an opening 27.

When the adapters are in place, secured by respective bolts 6, the faces 7 of respective adapters will lie along the circumference of a circle. A ring 8 is formed as shown in Figure 2 and provided with a plurality of openings, enabling respective fastening members 30 to secure the same to the adapters by the springs in a manner heretofore described. A slinger ring 10 is secured to the ring 8 by means of rivets 37. A ring 9 is adapted to be secured to the adapters by means of fasteners 30 and their coacting springs. A spinner ring 11 is secured to the ring 9 by means of bolts 38. A rubber shoe 39 may be fitted over

the nose spinner 11 to prevent ice from adhering thereto.

A feed pipe 40 is mounted in any suitable manner, as for example by bracket 41 secured to a part of the motor 42, and is adapted to conduct ice inhibiting fluid such as a mixture of alcohol and glycerine to the slinger ring 10. The after end of the slinger ring is provided with a curved flange 43. The portion of greatest diameter of the slinger ring is forward. The flanges 26 of respective conduits 24, mounted in the adapters, are secured to the slinger ring openings, being provided for the passage of fluid from the slinger ring through the conduits 25. The arrangement is such that the conduit 25 is progressively farther away from the axis of the propeller so that the flow of the ice inhibiting fluid will be toward the outlet adjacent the propeller blade under the influence of centrifugal force.

It will be observed that each of the adapters is rigidly mounted to the propeller hub and that the slinger ring and nose spinner assemblies are flexibly mounted to the adapters. In this manner, shock loading, due to vibration of the propeller blades, is minimized. The weight of the adapters, per se, is a minor portion of the load so that the major portion of the load is resiliently supported. The arrangement is such, further, that the nose spinner assembly or the slinger ring assembly may be quickly and readily removed. It is frequently necessary to remove the nose spinner assembly to inspect and service the parts of the variable pitch mechanism. This can be readily done by simply removing twelve fasteners 30, four for each adapter. The nose spinner prevents ice from collecting on the variable pitch mechanism and the rubber shoe prevents ice from collecting on the nose spinner.

In use, the airplane propeller, revolving, ice inhibiting fluid is fed through pipe 40 by any suitable means, as for example, by a pump or by gravity, from any source of supply and is deposited in the slinger ring 10. Centrifugal force forces the fluid outwardly through pipes 25 for deposit adjacent the base of each propeller blade, and centrifugal force will cause the de-icing fluid to pass outwardly around each propeller blade, preventing ice from collecting thereon. The curved flange at the rear of the slinger ring prevents ice inhibiting fluid from being blown out of the slinger ring by the suction action of the forward motion of the plane. The entire assembly, not counting the fastening means, comprises only five parts, namely, three adapters, the slinger ring assembly and the nose spinner assembly. In practice, I make the adapters and the rings 8 and 9 of steel, and the slinger ring and the nose spinner of aluminum. A complete assembly for a propeller having a diameter of eleven and one half feet weighs only fourteen pounds. An assembly of my invention has been in use on transport planes, in winter use under severe icing conditions, continuously for over 220 hours and has shown no signs of failure.

It will be observed that I have accomplished the objects of my invention. I have provided a nose spinner and slinger ring assembly for preventing the formation of ice on airplane propellers in which the entire unit may be readily mounted without the necessity of aligning and balancing the same, after assembly. It is understood, of course, that each adapter is made to weigh the same as the other adapters. The nose spinner is conveniently and expeditiously removable for servicing the variable pitch mechanism. The

adapter construction is of great strength per unit of weight and the entire assembly is extremely light.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. In combination with an airplane propeller having a hub and blades, adapters secured to said hub and extending between said blades, a first mounting ring, spring and cam fastening means for flexibly securing said first ring to said adapters, an ice inhibiting fluid distributing manifold carried by said first ring, a duct adapted to lead ice inhibiting fluid into said manifold, ducts carried by said adapters and communicating with said manifold for distributing ice inhibiting fluid from said manifold to points adjacent respective bases of the propeller blades under the action of centrifugal force, a second mounting ring, spring and cam fastening means for flexibly securing said second mounting ring to said adapters, and a hub cap secured to said second mounting ring.

2. In combination with an airplane propeller having a hub and blades, adapters secured to said hub and extending between said blades, a first mounting ring, means for flexibly securing said mounting ring to said adapters, an ice in-

hibiting fluid manifold carried by said first mounting ring, means providing communication between said ice inhibiting fluid manifold and points adjacent respective bases of the propeller blades, a second mounting ring, means for flexibly securing said second mounting ring to said adapters and a propeller carried by said second mounting means.

3. In combination with an airplane propeller having a hub and blades, adapters secured to said hub and extending between said blades, an annular ice inhibiting fluid manifold, means for flexibly securing said ice inhibiting fluid manifold to said adapters and means providing communication between said ice inhibiting manifold and respective points adjacent the bases of said propeller blades.

4. An assembly as in claim 3 wherein said means for flexibly securing said ice inhibiting fluid manifold to said adapters comprises a plurality of springs, means for securing said springs to said adapters and a plurality of cam means for coacting with said springs.

5. In combination with an airplane propeller having a hub and blades, adapters, means for rigidly securing said adapters to said hub and between said blades, an ice inhibiting fluid slinger ring and means for flexibly securing said slinger ring to said adapters.

6. An assembly as in claim 5 wherein said adapters comprise channel members having side flanges, corrugated metal sheets secured to said flanges, said flanges and said sheets being provided with openings adapted to receive bolts for securing said channel members to said propeller hub.

EDWARD B. BENSON.
